PROJECTION PRINTER PROCESS

Evelyn M. Harris, 46 Glenwood Ave., Pontiac, Mich.
Filed June 14, 1963, Ser. No. 287,810
1 Claim. (Cl. 88—24)

This invention relates to photographic equipment and more particularly to a projection printer for obtaining photographic reproductions.

The normal process of taking a picture, processing a negative, allowing drying time, printing a picture, processing and drying the print takes a great deal of time. Although many short-cut and fully automated processes for doing this work have been proposed in the past, none have proven too successful. These include the coin operated machines in dry goods stores and amusement parks as well as the more popular Polaroid systems in present use. The equipment is either too expensive or is a single print operation wherein any duplicate prints require the normal photographic processing procedure to be followed.

The need for a fast printing service, and obtaining multiple prints of a picture is most obvious as regards passport photographs. Here high standards are set for quality, specific sizes of the print and head image are essential, and usually the customer wants the work completed while he waits. Ordinarily the best service is between 24 hours and 3 days because of the processing time required after a picture is taken.

It is an object of this invention to disclose a new and novel means of reproductive printing which is both simple and fast and will have great use in the field of photography.

More particularly, it is an object of this invention to disclose a means of taking and printing a picture, as well as any desired number of duplicates within an exceptionally short time in comparison with presently known means of doing so.

It is an object of this invention to provide a device which will receive a positive paper film having a negative image and to process prints directly therefrom which require only the development and fixing thereof.

It is an object of this invention to provide a projection printer which is simple in construction, includes a minimum of parts, and is therefore economical to make and sell commercially.

It is an object of this invention to provide a projection printer which includes a simple lens and prism arranged to receive and project an image for printing and enlargement if desired from a positive paper negative.

It is an object of this invention to show, teach, and disclose a simple and expedient method and apparatus for printing passport photos which will revolutionize the passport and like photographic services where fast service is in high demand.

These and other objects and advantages to be gained in the practice of this invention will be better understood and appreciated upon a reading of the following specification in regard to a preferred embodiment of the invention and having reference to the accompanying drawings wherein:

FIGURE 1 is a schematic layout of a photographic studio showing the simplicity of the equipment required to practice this invention.

FIGURE 2 is a cross-sectional view of the projection printer of this invention.

FIGURE 3 is a front plan view of the projection printer with the front face cover door removed.

FIGURE 4 is an enlarged and cross-sectional view of the lens and prism holder used in the projection printer of this invention.

FIGURE 5 is a cross-sectional view of the lens and

prism holder of FIGURE 4 as seen in the plane of line 5—5 thereon and looking in the direction of the arrows.

The normal procedure for taking and printing pictures is to use a camera with a film from which is produced a transparent negative. Considerable time is required to process the transparent negative and to allow it to dry before printing can be done. The printing is done from the transparent negative by allowing light to pass through the negative on to light-sensitive photographic paper with the negative turned over so that the image is correctly oriented in the positive print obtained.

Another process involves the use of a positive paper film which is processed in a developer, washed, bleached and washed again, placed in a clearing solution, washed and then subjected to a finisher or toner solution to obtain a positive picture directly. Reproduction to obtain other prints requires a picture of the picture to obtain a transparent negative and the same procedure outlined previously.

Referring to the drawings now, the present invention makes use of a camera 10 which will take pictures on positive paper film. The subject to be photographed, as for passport pictures, is seated in a chair 12, in a studio room 14. The camera is focused, the subject is suitably illuminated, as by floodlight 16, and the picture is taken.

The photographer then retires to the dark room 18 and removes the positive paper film from the camera 10. The positive (paper backed) film is next immersed in a developer solution within such as pan 20 on a table or sink 22 in the dark room.

Normal procedure in the developing of positive film is to keep the film in the developer solution about 60 seconds. However, in the practice of this invention the film is immersed only long enough to obtain a negative image, which will be about one-tenth of the time or six seconds.

As soon as the negative image appears, the positive film with the negative image is removed from the developer, washed and passed through a fixer solution. For exceptionally fast service a five second immersion in a rapid acid fixer works perfectly.

The next step is to wipe the paper backed positive film, with its negative image, dry with a sponge. This type film is normally on waterproof type paper so that the film when wiped free of water droplets is not even damp in the normal sense and no drying is required.

At the conclusion of the work just mentioned, about fifteen seconds, give or take a few seconds for handling the film, the photographer has a positive paper opaque negative. The image is a left to right and black to white reversal of the object photographed.

The next step in the process taught by this invention is to print a positive picture directly on regular photographic paper. For this purpose a projection printer 24 has been devised and will now be described in sufficient detail to understand the rest of the procedure.

Referring to FIGURES 2 and 3:

The projection printer 24 includes an outer box 26 within which is disposed a lightproof box 28. The outer box 26 is formed with an opening 30 through its top wall through which the inner or dark box 28 is disposed. The front wall 32 of the dark box 28 is spaced from the front wall 34 of the outer box sufficiently to provide a chamber space 36 within which is provided a light source, such as the fluorescent lights 38 and 40.

An opening 42 is provided within the front wall 32 of the dark box 28. An adapter 44 is provided in this opening and it is formed to hold a camera lens 46 and an optical prism 48. The adapter 44 may be a square or rectangular fixture with a bore 50 at one end, suitably threaded to receive the lens ring 52, and extended arms 54 and 56 at the other end between which is received

and retained the prism 48. All that is important is that light received by the lens 46 be unobstructed in its passage to the prism 48 and its reflection by the prism towards the top of the dark box 28.

It will be noted that the prism 48 is disposed behind the lens 46 with its right angle sides 58 and 60 are disposed in parallel spaced relation to the plane of the lens 46 and the top of the dark box. This disposes the connecting side 62 of the prism, assuming a right angle prism, at a 45° angle for the light reflective purpose it serves.

An opening 64 is provided through the front wall 34 of the outer box 26, directly in line with the lens 46 and prism 48. The opening 64 is closed by a cover door 66 hinged as at 68 to the front wall 34 and it is formed to provide a pocket space 70 in which is disposed a film holder 72.

The dark box 28 includes a cover door 74 which closes its upper end and is hinged, as at 76, to the back wall thereof. On the inner side of the cover door 74 is provided a holder 78 which is receptive of photographic paper 80 on which the image from a film member 82 in the front door holder 72 is to be projected.

Continuing now to describe the process of this invention:

The positive paper film with the negative image which was previously described, and is now identified by the numeral 82, is placed in the holder 72 in the cover door 66 of the outer box 26. A piece of regular photographic paper, identified as 80 in the drawings, is placed in the holder 78 in the top closure door 74 of the dark box 28. Both cover doors are then closed and the lights 38 and 40 are turned on for about 6 seconds. Thereafter the photographic paper 80 is removed and processed in the regular manner through a developer solution, wash and fix.

When the negative image on the positive paper film 82 is illuminated by the light source, the light rays reflected from the surface thereof are received by the lens 46 and projected on to the reflective surface 62 of the prism 48. The reflected image is reversed by the prism 48 and projected in turn onto the photographic paper 80. As will be appreciated, the lens is properly positioned between the positive paper film 82 and the reflective wall 62 of the prism 48 for proper and sharp focus. Similarly the prism 48 is positioned relative to the photographic paper 80 and the lens 46 to obtain the same, enlarged, or reduction in size of the print desired.

Although the technique practiced is considerably different, the end result is much like projecting light *through* a transparent film negative, turned over, onto a piece of photographic paper. However, the time required to process a transparent negative is completely avoided and the procedure taught enables as many prints to be obtained from the same negative as may be desired.

The time required by a passport photographer using this process and the device described, to take a picture, process the positive paper negative, trim the negative and

put it in the projection printer, expose and develop the photographic printing paper, wash and dry four prints is approximately 20 minutes. Each print is made individually but from the same positive paper negative so that they are unquestionably identical.

Although no mention has been made of masking techniques, enlargement, color film, etc., it is to be understood that such of these as are standard and known may be used in the practice of this invention and such as are later devised or perfected and are adaptable for use in the manner and with the device disclosed are to be considered as contemplated hereby.

Further, although a preferred method and embodiment for the practice of this invention has been shown and described in detail, it will be appreciated that certain modifications and improvements are within the scope of the teachings set forth. Accordingly, such of these improvements and modifications as are within the spirit of the invention and are not specifically excluded by the language 20 of the hereinafter appended claim, are to be considered as inclusive thereunder.

I claim:

A photographic reproduction process for photo passport and other use requiring fast service, high quality and 25 lasting permanence, and comprising:
taking picture of a subject by focusing an image of such subject onto one positive sensitive paper, producing a negative image of said subject on said one paper,
30 damp-drying said one paper with said negative image, and immediately after the damp-drying of said one paper placing it in a fixed predetermined position and exposing the same and the negative image thereon to another positive sensitive paper also placed in a fixed predetermined position and at a substantially fixed predetermined focal length apart therefrom and under controlled artificial light to produce a positive picture of high quality and lasting permanence on said other paper.
